DESIGN FOR A DRAFTSMAN'S WELDING SYMBOL TEMPLATE

Richard John Burleigh, Vallejo, Calif.

Application April 9, 1945, Serial No. 118,910

Term of patent 7 years

(Cl. D52—1)

To all whom it may concern:

Be it known that I, Richard John Burleigh, a citizen of the United States, residing at No. 406 Winchester Street, Vallejo, in the county of Solano and State of California, have invented a new, original, and ornamental Design for Draftsman's Welding Symbol Templates, of which the following is a specification, reference being had to the accompanying drawing, forming part thereof.

Figure 1 is a plan view of a draftsman's welding symbol template, showing my new design.

Figure 2 is an edge view of the draftsman's welding symbol template shown in Figure 1.

I claim:

The ornamental design for a draftsman's welding symbol template, as shown.

RICHARD JOHN BURLEIGH.
